SIGNOR, BY MESNE ASSIGNMENTS, TO ACOUSTIC PRODUCTS COMPANY, OF NEW
YORK, N. Y., A CORPORATION OF DELAWARE

REENFORCED SOUNDING BOARD

Application filed March 15, 1927. Serial No. 175,456.

This invention relates to improvements in sounding boards.

The invention has for its principal object the provision of an improved sounding board 5 for efficient propagation of the lower notes of the musical register.

In my copending application, Serial No. 159,135 filed Jan. 5, 1927, for method and means for producing compressional waves, 10 I have disclosed an instrument for the faithful reproduction of musical sound embodying twelve tuned units corresponding to the notes of one of the lower middle octaves. These units are arranged to respond accurately to 15 any oscillation corresponding to their fundamentals, and to all the overtones which, of course, include the higher octaves. In said prior application, I pointed out, however, the necessity for providing other means 20 for producing the notes of lower register; and one such means consists in the association with twelve such units of a vibrating or sounding body primarily responsive only to such lower notes.

25 An important feature of the present invention relates to the provision of a sounding board having one or more intermediate ribs or rods, each having a relatively low natural period of vibration, in combination with 30 contiguous wings or webs actuated thereby for impressing compressional wave energy upon a surrounding natural medium.

Another feature relates to the tuning of 35 such a rod or rib to one predetermined musical note of the scale, and to the provision of an additional rod or rib tuned to a different note of the musical scale.

Another feature relates to the provision 40 of a sounding board, having a reenforcement rib in combination with an electromagnetic unit controlled by electric undulatory energy for impressing thereon vibratory energy of similar wave form.

Another feature relates to the provision 45 of a sound propagator having portions of relatively different thickness, the thinner portions being flexed into circular cross section.

Another feature relates to the provision of 50 adjustable supporting means for positioning the electromagnetic unit with respect to the

sounding propagator to obtain maximum effectiveness in impressing vibratory energy thereon.

Other objects of the invention will appear from the following description taken in connection with the accompanying drawings, in which

Fig. 1 is a side elevation of one form of sound propagator embodying features of the invention;

Fig. 2 is a front elevation thereof;

Fig. 3 is a cross-section taken on the line 3—3 of Fig. 2;

Fig. 4 is a cross-section of a modified form having the sounding board flexed transversely; and

Figs. 5, 6 and 7 are cross-sectional views of additional modified forms of the invention.

Like reference characters denote like parts in the several figures of the drawings.

In the following description and claims, parts, characteristic features and functions will be identified by specific means for convenience of expression, but they are intended to be as generic in their application to similar parts or equivalent construction as the art will permit.

Referring to the forms of the invention shown in Figs. 1, 2 and 3, there is provided a base 10, and a top piece 11, spaced therefrom and parallel therewith. Interconnecting the top piece 11 and the base 10 is a supporting rod 12, and a vibratory element or sound propagator 13. An electromagnetic unit 14 is slidably mounted as by a clamp 15 on the supporting rod 12, and includes a rod 16 forming an operative connection from the unit 14 to the sound propagator 13. In the form illustrated, this operative connection extends to a point 17 on the sound propagator 13 substantially fifteen per cent of the length of the sounding board from its end.

The sounding board 13 is shown as in Fig. 1 to be slightly bowed or flexed longitudinally into circular cross-section. It is understood that the electro-magnetic unit 14 is electrically controlled from a source of electric undulatory energy (not shown) such as

a radio receiving set or public address system, or the like.

The sound propagator 13 is shown as including a longitudinal enlarged portion 20 forming a rod or rib and preferably the point of application of the vibratory energy is on the line of the rod 20. The adjusting or contiguous portions 21, 22 of the vibratory element 13 form webs or wings of considerable superficial area in contact with the surrounding natural medium, and thus vibratory energy impressed upon the rod 20 is communicated to the contiguous portions of the sounding board and efficiently impressed upon the surrounding air.

The modified embodiment shown in Fig. 4 includes a sounding board 113, which instead of being bowed longitudinally, as in Fig. 1, is flexed transversely.

In the modified embodiment shown in Fig. 5, the vibratory element 13 and the electromagnetic unit 14 is provided as in Figs. 1 and 2, and an enlarged portion forming a rod or rib 220 is provided. The enlarged portion 220 is rectangular in cross-section. In the modified form shown in Fig. 6, the parallel spaced longitudinal rods or ribs 320, 323 are provided, each having an electromagnetic unit 314, 318 for actuating the same. Thus there are provided three web portions of reduced thickness as at 321, 322, 324 for efficiently impressing the vibratory energy upon the surrounding atmosphere.

In the modified form shown in Fig. 7 there are provided three longitudinal ribs or webs as at 420, 423, 425 having a corresponding plurality of electromagnetic units 414, 418, 419 for impressing vibratory energy thereon. Thus there are formed a plurality of webs or wings 421, 422, 424, 426.

Each longitudinal rod such as the rod 20, or the rods 420, 423, 425, may be independently tuned so as to have a relatively different natural period of vibration. Thus musical sounds of corresponding pitch may be efficiently propagated.

In operation, it is understood that the electromagnetic units 14, 314, 318 etc. are controlled from a source of undulatory electrical energy of complex wave form, having components of relatively low frequency corresponding to the lower notes of the musical register. In case the present sound propagator forms part of a device of the form illustrated in general in the copending application, hereinbefore referred to, it is understood that such components of low frequency will be selectively impressed upon the electromagnetic units herein designated. Each electromagnetic unit thus produces movement of its respective rod 16, and of the sounding rib connected thereto. This movement is communicated to the contiguous thinner portion of the sound propagator, and

compressional waves are thus produced in the surrounding atmosphere.

The invention upon which this application is based is broader than the specific embodiment shown and described for the purpose of illustrating at least one of the ways in which it may be employed. The scope of the invention is therefore to be understood as not being limited by the present specific description. I intend no limitations other than those imposed by the claims.

What is claimed is:

1. A sounding board including a tuned rod, means for impressing vibratory energy on said rod, and a web extending from the rod and receiving the vibratory energy from said rod.

2. A sounding board including a tuned rod, a web extending from and reenforced from the rod, said rod constituting a means for connection of the web to a support, means for impressing vibratory energy on said rod for transmission therefrom to said web.

3. A sounding board including a tuned rod, a web, said rod being substantially straight and extending throughout one dimension of the web, said rod reinforcing the web and constituting a means of connection therefor to a support, said web having a free edge outwardly of the support, and means for transmitting vibratory energy to said rod for transmission to said web.

4. A sounding board having portions of relatively different thicknesses, the thinner portions being flexed into circular cross-section, the thicker portion being tuned to a predetermined frequency.

5. In a sounding board, a reenforcement rib, and means for impressing vibratory energy on said rib at a point 15% of the length of the rib from an end thereof.

Signed at New York in the county of New York and State of New York this 14 day of March, A. D. 1927.
